UNITED STATES PATENT OFFICE.

EUGÈNE FRANÇOIS SUTER, OF LONDON, ENGLAND.

HAIR CURLER.

1,426,020.

Specification of Letters Patent. Patented Aug. 15, 1922.

Application filed March 4, 1922. Serial No. 541,049.

To all whom it may concern:

Be it known that I, EUGÈNE FRANÇOIS SUTER, a citizen of Switzerland, residing at 23 Grafton Street, Piccadilly, W. 1, city of 5 London, England, have invented certain new and useful Improvements in Hair Curlers, of which the following is a description.

This invention relates to improvements in hair curlers of the type generally used in 10 connection with the process of permanently waving hair, whereby, after a tress of hair has been wound upon the curler in either direction, the coils near the root end of the tress may be tightened without injury to the 15 hair or the curler, and be kept tight during the subsequent treatment.

It is well known that the process of permanently waving a tress of hair entails the 20 tight winding of the tress upon the curler preparatory to and during the subsequent treatment of steaming, and that as the hair is newest and thickest near the roots it is desirable for the coils to be tightest at the root end of the tress where they are most 25 difficult to wind tightly. This desideratum has hitherto been obtained by employing a curler (such as described in the specification of my British Patent No. 109718) having a short part to which the root end of 30 the tress is attached and a long part upon which the tress is wound and secured, the two parts being connected by a ratchet and pawl device so that the coils near their junction may be tightened and kept by holding 35 the short part and turning the long part. The disadvantages of such a device are that the tress can only be wound upon the curler in one direction, that the ratchet and pawl device is liable to fail from corrosion caused 40 by steaming, and that in order to hold the short part when turning the long part the former must be gripped with pliers which may damage its surface or the hair wound thereon.

According to this invention, while employing a curler of the above type, but without the ratchet and pawl device, I provide 45 the short part with an extension passing right through the hollow long part and terminating in a projection, which normally engages the long part and prevents it turning in either direction, but which when used as a handle for holding the short part releases the long part and allows it to be 50 turned in either direction. This projection is preferably a split handle which normally

springs open and engages the long part, but which when gripped closes and disengages the long part, so that the two operations of holding the short part and releasing the long 60 part are performed simultaneously by one hand, and the other hand is left free to turn the released long part. The engagement between the two parts may be frictional or a more positive engagement such as a pin and 65 hole, and the handle may be of a size and shape suitable for holding with the hand or may be only a small projection suitable for holding with pliers or other tool.

I now proceed to describe in detail and by 70 way of example one form of hair curler according to my invention and in connection with the accompanying drawings, in which—

Fig. 1 is a longitudinal section through a hair curler according to my invention;

75

Fig. 1^a is a detail of a portion of the exterior of the hair curler illustrated in Fig. 1.

Fig. 2 is a perspective view of a second form of hair curler according to my invention.

80

In Figure 1 *a* is the short part provided with an extension *c* passing through the hollow long part *b* and terminating in the two springs *d*, and *d*₂, which project beyond the end of the long part *b*, and to which are attached the split handles *e*₁ and *e*₂. A portion *f*₁ and *f*₂ of each split handle projects into the tube *b*, and may fit closely therein when pressed apart by the springs *d*₁ and *d*₂ so as to form a frictional engagement between the parts *a* and *b*, but I prefer to provide each portion *f*₁ and *f*₂ with pins *g*₁ and *g*₂, which fit into the diametrically opposite holes of a ring of holes in the tube *b* and provide a positive engagement between the 95 parts *a* and *b*.

With this curler the root end of a tress of hair is bound together and attached to the short part *a* (which is provided with the usual slot *h* for this purpose), the tress 100 is wound in either direction and secured upon the long part *b*, the split handles *e*₁ and *e*₂ are gripped with one hand, thus holding the short part *a* and releasing the long part *b* which is rotated by the other hand so 105 as to tighten the wound tress of hair, and finally the split handles *e*₁ and *e*₂ are released and the springs *d*₁ and *d*₂ push the pins *g*₁ and *g*₂ into diametrically opposite holes *k* in the tube *b* and keep the tress 110 tightly wound during the subsequent treatment.

Figure 2 shows a modification in which the end of the long part *b* is made square and the springs *d*₁ and *d*₂ press against the flats of the square and give a positive engagement without the use of pins and holes. Projecting springs without handles are very convenient for holding with pliers, and provide a means for using such a tool without damaging the surface of the part *a* or the hair wound thereon.

Having now particularly described and ascertained the nature of my said invention, and in what manner the same is to be performed, I declare that what I claim is:

1. A hair curler comprising in combination a long hollow part, and a short part mounted at one end of said long part and having an extension passing through said hollow part and terminating in a projection which normally engages said hollow part

and prevents it turning in either direction with respect to said hollow part, said extension being releasable from said hollow part and permitting said short part to be turned in either direction, for the purpose 25 described.

2. A hair curler comprising in combination a long hollow part, a short part at one end of said hollow part, and an extension fixed to said short part and running through 30 said hollow part, said extension including a pair of springs having their one ends fixed to said extension, and handle pieces fixed to said springs and extension without said hollow part at the end opposite said short 35 part, said handle pieces having projections thereon within said hollow part and said hollow part having apertures therein for receiving said projections.

EUGÈNE FRANÇOIS SUTER.
